UNITED STATES PATENT OFFICE.

GIOSPE S. VAMPA, OF NEW YORK, N. Y.

CLOSET-BOWL.

1,239,311

Specification of Letters Patent.

Patented Sept. 4, 1917.

Application filed April 14, 1914. Serial No. 331,798.

To all whom it may concern:

Be it known that I, GIOSEPE S. VAMPA, a citizen of United States, residing at New York city, in the county of New York and State of New York, have invented certain new and useful Improvements in Closet-Bowls, and do hereby declare the following to be a full, clear, and exact description of the invention, such as will enable others skilled in the art to which it appertains to make and use the same.

This invention relates to improvements in closet bowls and its primary object is to provide a closet bowl of simple construction, which may be easily cleaned, and which discharges its contents readily, when flushed.

Another and more specific object of the invention is to provide a water closet bowl having intake and discharge openings arranged on opposite sides thereof, the former being disposed above the latter.

A further object of the invention is to provide a water closet bowl having a horizontal wall or shelf formed therein across which the water flows, said shelf being formed on one side with an opening communicating with a tortuous discharge channel which forms a trap.

With these and other objects in view as will become more apparent as the description proceeds, the invention consists in certain novel features of construction, combination and arrangement of parts as will be herein-after more fully described and claimed.

For a complete understanding of my invention, reference is to be had to the following description and accompanying drawings, in which—

Figure 1 is a top plan view of my improved bowl with the seat raised;

Fig. 2 is a vertical transverse sectional view, and

Fig. 3 is a detail view, of the spring seat.

Referring in detail to the drawings by numbers, 5 designates the bowl generally, which comprises a hollow body having an approximately circular reinforcing flange 6 extending around its upper edge and a horizontal wall or shelf 7 formed intermediate its top and bottom. This shelf extends, as clearly shown in Fig. 1, entirely across the bowl, and is cut away on one side to form a discharge opening 8 elliptical in shape. A tortuous or serpentine channel 9 leads from the opening 8 to a circular opening 10 formed in the bottom of the bowl for connection with

a drain pipe 11. The channel 9 is formed by a wall 12 and a flange 13.

The body of the bowl 5 is formed just under the flange 6 on the opposite side from the opening 8, with an opening 14 into which a water pipe 15 extends. As a means for directing the water silently against the shelf 7 so as to flow over the entire surface thereof and discharge through the opening 8 into the channel 9, I have provided an approximately semi-spherical member 28 that is secured by suitable fastening means to the bowl forwardly of the open end of the water pipe 15 so that the water in discharging from the pipe 15 engages the member 28 and is directed against the side of the shelf 7 of the bowl as stated.

The seat 17 is secured to the offset portion 18 of the bowl by a pair of suitable biages 19 and is held normally in a raised position by a pair of expansive helical springs 20 which are secured at their upper ends within sockets 21 formed in the seat and at their lower ends within sockets 22 formed in the extension 18. This construction allows the seat to be swung downwardly against the flange 6 when in use and be returned to its normal raised position when pressure thereon is removed. My improved water closet bowl may be silently flushed, easily cleaned and cheaply manufactured.

The flange 6 and horizontal wall or shelf 7 are disposed in approximately spaced parallel relation to each other and thus form an approximately horizontal channel. As a means for preventing the back flow of gases and liquids, I provide a valve 23 that is pivoted as at 24 to the underface of the shelf or wall 7 and arranged to seal the passage 95 formed as described. The valve 23 is formed in the nature of a plate and at its free end engages a shoulder 25 formed on the outer end of the flange 13 as clearly shown in Fig. 2 in the drawings. This shoulder 25 is formed by recessing or cutting away the flange 13 and limits the inward movement of the valve 23. It will thus be seen that the valve 23 is free to move outwardly when water is discharged into the passage through the opening 8 but will readily close upon the back flow of liquid with relation to the bowl.

As a means for permitting the bowl to be readily and easily cleaned I have provided a screw cap 26 that is turned into an opening 110 27 formed in the wall of the passage 9 intermediate the ends thereof as clearly shown in

Fig. 2 in the drawings. This construction permits ready and easy access to the interior of the passage so that cleaning thereof may be had.

5 While I have shown and described the preferred embodiment of my invention, it will be understood that minor changes in construction, combination and arrangement of parts may be made without departing from 10 the spirit and scope of the invention as claimed.

Having thus described my invention, I claim:—

15 A closet bowl comprising a hollow body provided at its upper edge with a circular reinforcing flange, a horizontally extending shelf formed intermediate the top and bottom of said bowl, said shelf extending from side to side across the bowl and provided 20 with an elliptical opening at one side thereof, an inwardly extending flange formed at the side wall adjacent the opening and extending under the shelf forming a passage

which communicates with the upper side of said shelf, a flap valve closing the outer end 25 of said passage and hingedly secured to the under side of the shelf, the side wall of the body opposite the elliptical opening being provided with an opening which is in direct alignment with the passage which the flap 30 valve closes, a plug for closing said wall opening, a shallow pan formed integrally with the vertical wall immediately beneath the end of said inwardly extending flange, a curved tubular wall extending from the 35 front edge of the pan and from the under side of the said flange to form an outlet opening, and a drain pipe associated with the last named opening.

In testimony whereof I affix my signature 40 in presence of two witnesses.

GIOSEPE S. VAMPA.

Witnesses:

PATRICK O'KEEFE,
MICHAEL LYNCH.
